METAL HYDROCARBYL ORTHOPHOSPHATE GASOLINE ADDITIVE

Anthony J. Revukas, Cranford, N.J., assignor to Cities Service Oil Company, Bartlesville, Okla., a corporation of Delaware

No Drawing. Continuation-in-part of application Ser. No. 413,631, Nov. 24, 1964. This application Dec. 23, 1965, Ser. No. 516,136

Int. Cl. C10I 1/26

U.S. Cl. 44—69

18 Claims 10

ABSTRACT OF THE DISCLOSURE

A metal hydrocarbyl orthophosphate gasoline additive composition is disclosed, wherein the additive is in the amount of between 0.001 and about 5.0 times the theoretical amount (theories) to react stoichiometrically with the lead in the gasoline combustion product. A preferred metal hydrocarbyl orthophosphate additive is represented by the general formula:

wherein M represents manganese, thorium, and metals of Groups I-B, II-A, VI-B and VIII of the Periodic Table, n is a number equal to the valence of the metal M, and R and R' each represent hydrocarbyl radicals having from 2 to 30 carbon atoms and soluble to the required extent in gasoline; preferably at least one of the R and R' radicals represents a branched chain hydrocarbyl radical.

This invention relates to novel and improved gasoline compositions containing certain metallic orthophosphate compounds.

This application is, in part, a continuation of my pending application, Ser. No. 413,631, filed Nov. 24, 1964, which in turn is a continuation-in-part of my copending application Ser. No. 127,858, filed July 31, 1961, now abandoned.

The use of lead compounds to increase the octane rating of gasoline is extremely common. Unfortunately, the addition of lead, while substantially increasing the octane ratings of gasolines to which it is added, at the same time has several drawbacks. Of these drawbacks, the most serious is probably the tendency of the lead to increase undesirable surface ignition in the combustion chambers of the internal combustion engines in which the leaded gasoline is used. It has been the practice previously to utilize various phosphorus compounds in an attempt to reduce or prevent such surface ignition, but the use of such compounds has generally led to additional difficulties, such as lead deposits on cylinder heads and valves.

It is, therefore, an object of the invention to provide an improved gasoline composition.

It is a further object of the invention to provide an improved gasoline composition especially adapted to resist surface ignition.

The improved gasoline compositions provided by the invention comprise as additive compounds metallic orthophosphates represented by the general formula:

wherein M represents a metal selected from the group consisting of manganese and thorium and Groups I-B, II-A, VI-B and VIII of the Periodic Table, X is halogen, n and

2

a are numbers so selected that n equals the valence of the metal M and a equals zero except when the valence of the metal M equals 5, then a equals 2 and n equals 3, and R and R' each represent a hydrocarbon radical having from 2 to about 30 carbon atoms. Preferred metallic orthophosphates for the purpose of this invention are those represented by the general formula:

wherein M, R and R' are as defined above and n is an integer of from 2 to 4 and is equal to the valence of the metal M.

In such compounds the valence of the metal M usually depends upon the starting material used. Preparation of these compounds is discussed in greater detail below.

R and R' may represent identical or different hydrocarbon radicals. While any hydrocarbon radical having between 2 and about 30 carbon atoms and soluble to the required extent in gasoline may be used, at least one of R and R' preferably represents a branched-chain acyclic hydrocarbon radical. Such radicals are generally more soluble in gasoline than other hydrocarbon radicals, thereby facilitating the use of the novel compounds of the present invention as gasoline additives. Since chains of more than about 30 carbon atoms are generally difficult or impossible to dissolve in gasoline compositions, it is preferred that the hydrocarbon radicals of the orthophosphates utilized in the present invention each have between about 2 and about 30 carbon atoms. It is particularly preferred that the hydrocarbon radicals represented by R and R' be acyclic aliphatic hydrocarbon radicals containing from about 6 to about 22 carbon atoms, particularly C₆ to C₂₂ branched-chain aliphatic hydrocarbon radicals.

Typical R and R' groups would include, ethyl, propyl, isopropyl, butyl, isobutyl, tert-butyl, pentyl, isopentyl, hexyl, isohexyl, 2,2,4-trimethylpentyl, 3-methylpentyl, 2,2-dimethylbutyl, 2,3-dimethylbutyl, heptyl, isoheptyl, 3-methylhexyl, 3,3-dimethylpentyl, octyl, 2,3-dimethylhexyl, 2,4-dimethylhexyl, 2-ethylhexyl, 2-ethylbutyl nonyl, decyl, undecyl, dodecyl, tridecyl, tetradecyl, pentadecyl, hexadecyl, heptadecyl, octadecyl, nonyldecyl, eicosyl, heneicosyl, docosyl, tricosyl, tetracosyl, pentacosyl, hexacosyl, heptacosyl, octacosyl, nonacosyl, triacosyl, phenyl, naphthyl, benzyl, o-cresyl, p-cresyl, m-cresyl, dodecylphenyl, octylphenyl, ethylphenyl, diphenyl, B-phenylethyl, omega-phenylhexyl, cyclohexyl, cyclobutyl, cyclooctyl, cyclopentyl, butenyl, octenyl, 2,3-dimethylpentenyl, 2-ethylhexenyl, linoleyl, oleyl, etc.

Compounds of the present invention having branched-chain alkyl hydrocarbon radicals include, for instance, the following:

nickel di[bis (2-methylpropenyl) orthophosphate]
manganese di[bis (3-butyloctacosyl) orthophosphate]
copper di[bis (5-pentylhexadecyl) orthophosphate]
beryllium di[bis (2-ethyl-5-butyltridecyl) orthophosphate]
silver [bis (2,4-diethyloctyl) orthophosphate]
chromium tri[bis (2-methyloctenyl) orthophosphate]
iron tri[bis (i-propyl) orthophosphate]
nickel di[bis (2-ethylhexyl) orthophosphate]
molybdenum III tri[i-propyl, propyl orthophosphate]
magnesium di[i-propyl, 2-propyldecyl orthophosphate]
nickel di[bis (isodecyl) orthophosphate]
ruthenium tri[2-ethylhexyl, butenyl orthophosphate]
osmium II [(2-ethylhexyl, octyl), (i-puropyl, butyl) orthophosphate]
nickel di[isodecyl, 2-ethylhexyl orthophosphate]
tungsten hexa[2-ethylhexyl, i-butyl orthophosphate]

dichloromolybdenum tri[bis (2-ethylhexyl) orthophosphate]
chromium tri[bis (2,3-dimethylpentenyl) orthophosphate]
magnesium di[bis (2-ethylhexyl) orthophosphate]

Compounds of the present invention having alkylaryl hydrocarbyl radicals include, for instance, the following:

thorium tetra[bis (methylphenyl) orthophosphate]
tungsten hexa[bis (octylphenyl) orthophosphate]
nickel di[bis (methylphenyl) orthophosphate]
calcium di[bis (pentylphenyl) orthophosphate]
gold tri{octylphenyl, pentylphenyl orthophosphate}
strontium di[bis (methylphenyl) orthophosphate]
nickel di[bis (hexylphenyl) orthophosphate]
cobalt tri[bis (methylnaphthyl) orthophosphate]
rhodium II[(pentylnaphthyl, propyl) di (methylphenyl) orthophosphate]
dichloromolybdenum tri[bis (ethylphenyl) orthophosphate]

Compounds of the present invention having both alkyl and alkylaryl hydrocarbyl radicals include, for instance, the following:

barium di[2-ethylhexyl, methylphenyl orthophosphate]
iridium II[(butyl, ethylhexyl), (methylphenyl, propyl) orthophosphate]

Compounds of the present invention having aryl hydrocarbyl radicals include, for instance:

radium di[bis (phenyl) orthophosphate]
palladium tri[phenyl, naphthyl orthophosphate]
nickel II[naphthyl, 2-ethylhexyl orthophosphate]

Compounds of the present invention having arylalkyl hydrocarbyl radicals include, for instance:

nickel di[bis (phenylmethyl) orthophosphate]
platinum II[(naphthylethyl, butyl), (2-ethylhexyl, phenylhexyl) orthophosphate]
nickel di[i-butyl, naphthylmethyl orthophosphate]

Compounds of the present invention having alicyclic hydrocarbyl radicals include, for instance:

nickel di[cyclobutyl, 2-ethylhexyl orthophosphate]
cobalt tri[bis (cyclohexyl) orthophosphate]
manganese di[bis (cyclohexyl) orthophosphate]
calcium di[bis (cyclopentyl) orthophosphate]

Compounds of the present invention having straight chain hydrocarbyl radicals include, for instance, the following:

cobalt tri[bis (octyl) orthophosphate]
magnesium di[bis (octenyl) orthophosphate]
nickel di[bis (ethyl) orthophosphate]
calcium II[di (butyl), di(pentyl) orthophosphate]
nickel di[2-ethylhexyl, butenyl orthophosphate]
nickel di[(butyl, isodecyl) orthophosphate]
copper di[bis (decyl) orthophosphate]

The novel compounds described above are especially useful as gasoline additives in forming novel gasoline compositions adapted to resist surface ignition. In addition to resisting surface ignition, these additives generally inhibit rust and carburetor icing. In accordance with a preferred embodiment of the present invention a gasoline composition is provided which comprises a major proportion of a leaded hydrocarbon base fuel boiling in the gasoline range and containing between about 0.001 and about 5.0 theories of a metallic hydrocarbyl orthophosphate of the type described above. The leaded hydrocarbon base fuel comprises at least 50 volume percent and preferably at least 75 volume percent of the gasoline composition.

By the term "leaded gasoline," "leaded hydrocarbon base fuel boiling in the gasoline boiling range" and similar terms is meant a petroleum fraction boiling in the gasoline range (e.g., between about 50° and about 450° F.) to which has been added a small amount, such as

between about 0.1 and about 6.0 cc. per gallon, of a metallo-organic antiknock compound such as tetraethyl lead (TEL), tetramethyl lead (TML), tetraisopropyl lead, etc. Lead is frequently present in gasoline compositions of the present invention in the form of TEL, TML or mixtures of the same which may be present in suitable amounts such as between about 0.1 and about 6.0 cc. per gallon of gasoline composition, more usually between 0.5 and about 4.0 cc. per gallon.

The novel metallic orthophosphates described above for use in leaded gasoline compositions in accordance with the present invention are present in suitable amounts such as between about 0.001 and about 5.0 theories, preferably between about 0.02 and about 2.0 theories. The term "theory" in this context is intended to designate the amount of metal hydrocarbyl orthophosphate additive that would be needed in a gasoline in order that the metal and phosphorus atoms in the metal hydrocarbyl orthophosphate would be able to react stoichiometrically with all the lead in the lead antiknock compound present in a gasoline to form the appropriate lead compound upon combustion in an engine. The "theory" concept may be based on the metal only, on the phosphorus only, or on both elements in the metal hydrocarbyl orthophosphate. Thus, for example, the additive dichloromolybdenum tri[bis(2-ethylhexyl) orthophosphate] could react with TEL and TML to produce lead orthophosphate and lead molybdate. In this example the theories of additive employed would be based on the phosphorus required to form lead orthophosphate and on the metal molybdenum to produce lead molybdate. If the metal in the metal hydrocarbyl orthophosphate additive does not combine with the lead in the gasoline to form a compound upon combustion in an engine, then the theory concept is based on the phosphorus in the additive. To illustrate, nickel di[bis(isodecyl) orthophosphate] in a gasoline with TEL forms only lead orthophosphate upon combustion, as no compounds of lead with nickel are known to exist.

In addition to the above-described compounds, gasoline compositions contemplated by the present invention may include one or more other ingredients such as lead scavengers, gum inhibitors, lubricants, rust inhibitors, metal deactivators or other special purpose additives.

Lubricants suitable for use in the above-described gasoline compositions may include, for instance, light hydrocarbon lubricating oils having viscosities at 100° F. of between about 50 and about 200 Saybolt Universal seconds (SUS) and viscosity indexes (VI) of between about 30 and about 120 with oil having a viscosity of about 100 SUS being preferred. Such oils may be present in suitable amounts such as between about 0.1 and about 1.0 volume percent of the gasoline composition.

When using lead compounds such as TEL, it is frequently found desirable to include with the lead a suitable lead scavenger for reducing the deposit of lead compounds within the combustion chamber. Such lead scavengers include, for example, halohydrocarbon compositions such as ethylene dibromide and ethylene dichloride.

Gum inhibitors suitable for use in the above-described gasoline compositions include conventional gum inhibitors such as 2,6-di-tert-butyl-p-cresol. Such gum inhibitors may be present in suitable amounts such as between about 0.001 and about 0.006 volume percent of the gasoline composition. Likewise, a suitable metal deactivator is for example N,N'-disalicylidene-1,2-diaminopropane.

Gasoline compositions of the present invention may be illustrated by the following examples. It should be understood that any of the other novel additive compounds contemplated by the invention, such as those described above, may be used in such gasoline compositions in place of or in addition to the additives specified below.

Example 1

A gasoline composition having excellent surface igni-

tion characteristics may be prepared by adding the following ingredients to a suitable base gasolene:

TEL cc. per gallon 2.2
Dichloromolybdenum tri[bis(2-ethylhexyl) ortho-phosphate] theories 0.05

The base gasolene used in blending this and other gasolene compositions of the invention may be a gasolene having the following characteristics:

Distillation:

IBP 101° F.—	
10% evaporation	° F. 130
20%	° F. 149
30%	° F. 168
50%	° F. 210
70%	° F. 260
90%	° F. 328
End point	° F. 409
Recovery	percent 98.5
Residue	do 1
Gravity	° API 58.2

Example 2

Another suitable gasolene composition is prepared by adding the following ingredients to a suitable base gasolene:

TEL cc. per gallon 0.5
Cobalt [(propyl, cyclopentyl) di(2-ethylhexyl) orthophosphate] theories 0.25

Example 3

Another suitable gasolene composition is prepared by adding the following ingredients to a suitable base gasolene:

TEL 4.0 cc. per gallon.
Manganese di(2-ethylhexyl, octyl) orthophosphate 0.5 theories.
Lubricating oil 1.0 volume percent (100 SUS, 95 VI).

Example 4

Another suitable gasolene composition is prepared by adding the following ingredients to a suitable base gasolene:

TEL cc. per gallon 6.0
Nickel di[bis(2-ethylhexyl) orthophosphate] theories 5.0

Example 5

TEL cc. per gallon 0.1
Magnesium di[bis(2-ethylhexyl) orthophosphate] theories 0.005

Example 6

Another suitable gasolene composition is prepared by adding the following ingredients to a suitable base gasolene:

TEL 2.2 cc. per gallon.
Chromium tri[bis(tri-*an*isopropylphenyl) orthophosphate] 0.1 theories.
Lubricating oil 0.25 volume percent (100 SUS, 95 VI).

Example 7

Another suitable gasolene composition is prepared by adding the following ingredients to a suitable base gasolene:

TML cc. per gallon 2.5
Chromium di[bis(o-cresyl) orthophosphate] theories 0.15

Example 8

Another suitable gasolene composition is prepared by

adding the following ingredients to a suitable base gasolene:

TEL cc. per gallon 0.8
Tungsten tetra[bis(α-naphthyl) orthophosphate] theories 0.06

Example 9

Another suitable gasolene composition is prepared by adding the following ingredients to a suitable base gasolene:

TML cc. per gallon 4.0
Iron tri[2-ethylhexyl, α-naphthyl orthophosphate] theories 3.5

Example 10

Another suitable gasolene composition is prepared by adding the following ingredients to a suitable base fuel:

TEL cc. per gallon 2.33
Osmium tetra[bis(octyl) orthophosphate] theories 2.0

Example 11

Another suitable gasolene composition is prepared by adding the following ingredients to a suitable base fuel:

TEL cc. per gallon 1.8
Thorium tetra[bis(cyclohexyl) orthophosphate] theories 1.8

Example 12

Another suitable gasolene composition is prepared by adding the following ingredients to a suitable base fuel:

TEL cc. per gallon 1.2
Manganese di[bis(linoleyl) orthophosphate] theories 1.5

The metallic orthophosphate compounds utilized additives in accordance with the present invention may be prepared in any suitable manner. According to one method of preparation, a suitable organic hydrogen phosphate or a mixture of such phosphates is placed in a reaction flask together with about half its volume of a suitable solvent such as dry toluene. The reaction flask is preferably equipped with a mechanical stirrer, thermometer, gas inlet tube, reflux condenser and a pressure equalizing funnel with its long stem dipping into the solution. The temperature in the reaction flask is raised to between about 110° and about 130° C. while stirring vigorously and a suitable salt such as a chloride of the desired metal with an equal volume of the solvent is added in spurts by means of the pressure equalizing delivery funnel. When a chloride is used, hydrogen chloride is evolved copiously by the reaction. Stirring and heating under reflux to 130° C. is continued until evolution of hydrogen chloride stops. Removal of by-product hydrogen chloride is promoted by flushing the reaction flask with dry nitrogen by means of the gas inlet tube. The solvent is removed by distillation at reduced pressure such as 10 to 80 millimeters, the final temperature being about 130° C. The yield of product is usually between about 85 and about 95% of theory based on hydrogen phosphate.

Example 13

Nickel di[bis(2-ethylhexyl) orthophosphate] was prepared from the following ingredients:

32.6 gm. (0.137 mole) nickel chloride hexahydrate
80.6 gm. (0.25 mole) di(2-ethylhexyl) hydrogen phosphate
10.0 gm. sodium hydroxide in 100 ml. water

The acid phosphate was weighed into a 3-neck round bottom flask equipped with mechanical stirrer, thermometer, and condenser. About 100 ml. of water was added to the flask and the mixture was stirred while the sodium hydroxide solution was added slowly. The temperature in the flask rose from 26° to 46° F. About 200 ml. of

toluene was added and the temperature increased by external heating to 80° C. At this time the nickel chloride hexahydrate in 50 ml. of H₂O was added. The reaction temperature was raised to 87° C. and maintained at this level with vigorous stirring for 16 hours. After this time the contents were transferred to a separatory funnel and the aqueous phase drawn off and discarded. The organic layer was washed with water, dried over anhydrous Na₂SO₄, filtered to remove the hydrated salt and finally subjected to distillation to remove solvent.

The product was a brown, viscous material.

Example 14

In order to prepare dichloromolybdenum tri[bis(2-ethylhexyl) orthophosphate], 212 grams (0.66 mole) of commercial di(2-ethylhexyl) hydrogen phosphate in 150 ml. of toluene and 55 grams (0.2 mole) molybdenum pentachloride in 200 ml. of toluene were caused to react. When evolution of by-product hydrogen chloride stopped, toluene was stripped from the product, which was then washed with water and taken up in n-pentane. After drying over anhydrous sodium sulfate, the pentane solution was filtered and the filtrate subjected to distillation to remove pentane. The liquid residue was heated to 120° C. at 20 mm. pressure. An olive green liquid product weighing 203 grams resulted. Its density was 1.109 at 20° C. and the molybdenum content was 8.50 percent.

Additional metallic orthophosphate additives were prepared according to the procedures described above from suitable starting materials as follows:

Starting materials	Amount (grams)	Product	Amount (grams)
Cobaltous acetate tetrahydrate.	62	Cobalt di[bis(2-ethylhexyl) orthophosphate].	158
Di(2-ethylhexyl) hydrogen phosphate.	161		
Manganous chloride tetrahydrate.	22	Manganese di[bis(2-ethylhexyl) orthophosphate].	60
Di(2-ethylhexyl) hydrogen phosphate.	64.5		

Other compounds of the present invention may be prepared from suitable starting materials. For instance, the following compounds may be prepared from the indicated starting materials with the use of suitable solvents such as toluene, heptane, etc.

Starting materials	Amount (grams)	Product
Magnesium chloride.....	56	Magnesium di[bis(2-ethylhexyl) orthophosphate].
Di(2-ethylhexyl) hydrogen phosphate.	161	
Chromic chloride.....	17.5	Chromium tri[bis(triacontylphenyl) orthophosphate].
Triacetyl-phenyl-hydrogen phosphate.	178.2	
Chromous chloride.....	13.4	Chromium di[bis(o-cresyl) orthophosphate].
Di(o-cresyl) hydrogen phosphate.	55.6	
Tungsten tetrachloride.....	35.8	Tungsten tetra[bis(α-naphthyl) orthophosphate].
Di(α-naphthyl) hydrogen phosphate.	140	
Ferric chloride.....	17.8	Iron tri(2-ethylhexyl, α-naphthyl) orthophosphate.
2-ethylhexyl, α-naphthyl-hydrogen phosphate.	108.9	
Ruthenium tetrachloride.....	13.3	Ruthenium tetra[bis(octylphenyl) orthophosphate].
Di(octylphenyl) hydrogen phosphate.	105	

In order to evaluate the characteristics of gasoline compositions of the present invention, a number of gasoline compositions were prepared containing metallic orthophosphate additives of the present invention as indicated in Table I below. These gasoline compositions were subjected to single cylinder engine deposit tests as described below. The base gasolines used in formulating the gasoline compositions tested were similar to the base gasoline of Example 1. The base gasolines of runs No. 1 through 3 contained 2.2 cc. per gallon TEL and 0.25 vol. percent 100 neutral (95 VI) light lubricating oil.

70 75

The base gasoline of run 4 contained 2.03 cc. per gallon TEL. The single cylinder engine deposit tests were run in CFR engines having L head assemblies and compression ratios of 7 to 1. Each test consisted of alternating periods of operation under idling conditions for 50 seconds followed by operation under full load conditions for 150 seconds. These cycles were continued for a total test time of 40 hours for each test. During these tests the engine air intake temperature was maintained at 115° F. while the oil temperature was maintained at 160° F. and the coolant temperature at 150° F. During the idling portions of the tests the engines were operated with an air to fuel ratio of 12 to 1 at 600 r.p.m. while during the full load portions of the tests the engines were operated with air to fuel ratios of 13 to 1 and at 900 r.p.m. During the test, the number of wild pings (indicating preignition) was counted by an Erwin Instrument Co. Wild Ping Counter. At the end of the test the average of the wild pings per hour was determined by plotting the total wild pings versus time and taking the slope of the curve. This measurement served as a reliable indication of the surface ignition characteristics of the fuel being tested.

The results of the single cylinder engine deposit test are given in Table I below. Each run involved a test of a base gasoline and a test of the same base gasoline containing the indicated metallic orthophosphate additive. While the base gasolines used were generally similar, they had been stored for varying lengths of time before testing, thus affecting their performance in the tests. The test results reported below thus prove valid comparisons within each run between the performance of a base gasoline and the performance of the same gasoline containing the indicated additive but do not provide valid comparisons between the base gasolines used in the various runs.

35 TABLE I.—RESULTS OF SINGLE CYLINDER ENGINE DEPOSIT TESTS

Run No.	Orthophosphate additive	Theories of additive	Average wild pings per hour of base gasoline	
			Without additive	With additive
1	Cobalt di[bis(2-ethylhexyl) orthophosphate].	0.2	21	2
2	Manganese di[bis(2-ethylhexyl) orthophosphate].	0.2	31	1
3	Nickel di[bis(2-ethylhexyl) orthophosphate].	0.2	19	1
4	Dichloromolybdenum tri[bis(2-ethylhexyl) orthophosphate].	0.05	586	15

50 55 60 65

Table I shows clearly that the addition of metallic orthophosphates of the present invention to the base gasolines resulted in gasoline compositions having very much improved surface ignition characteristics as evidenced by the extremely small number of wild pings compared with the corresponding base gasolines.

While the invention has been described above with respect to certain preferred embodiments thereof, it will be understood by those skilled in the art that various changes and modifications may be made without departing from the spirit and scope of the invention and it is intended to cover all such changes and modifications in the appended claims.

Therefore, I claim:

1. A gasoline composition consisting essentially of a major proportion of a leaded hydrocarbon base fuel boiling in the gasoline range and containing between about 0.001 and about 5.0 theories of an additive having the formula:

wherein M is a metal selected from the group consisting of manganese and thorium and the metals of Groups I-B, II-A, VI-B and VIII of the Periodic Table, n equals the valence of metal M, and R and R' each represent a hydrocarbon radical having from 2 to about 30 carbon atoms.

2. Gasolene composition as in claim 1 wherein said metal is manganese.
3. Gasolene composition as in claim 1 wherein at least one of R and R' is a branched-chain hydrocarbon radical.
4. Gasolene composition as in claim 3 wherein said metal is nickel and n is 2.
5. Gasolene composition as in claim 1 wherein R and R' are acyclic aliphatic hydrocarbon radicals containing from about 6 to about 22 carbon atoms.
6. Gasolene composition as in claim 5 wherein both R and R' are branched-chain hydrocarbon radicals.
7. Gasolene compositions as in claim 6 wherein said metal is nickel and n is 2.
8. Gasolene composition as in claim 1 which contains between about 0.02 and about 2.0 theories of said additive.
9. Gasolene composition as in claim 1 wherein said leaded hydrocarbon base fuel is a petroleum fraction boiling between about 50° C. and about 450° C. to which has been added between about 0.1 and about 6.0 cc. per gallon of tetraethyl lead.
10. Gasolene composition as in claim 9 wherein the amount of tetraethyl lead is from about 0.5 to about 4.0 cc. per gallon.
11. Gasolene composition as in claim 1 wherein said additive is cobalt di[bis(2-ethylhexyl) orthophosphate].
12. Gasolene composition as in claim 1 wherein said additive is manganese di[bis(2-ethylhexyl) orthophosphate].
13. Gasolene composition as in claim 1 wherein said additive is nickel di[bis(2-ethylhexyl) orthophosphate].
14. Gasoline composition as in claim 1 wherein said additive is nickel di[bis(isodecyl) orthophosphate].
15. Gasoline composition as in claim 1 wherein said metal is nickel, n is 2, and R and R' are alkylaryl groups.
16. Gasoline composition as in claim 1 wherein said additive is nickel di[bis(methyl phenyl) orthophosphate].
17. Gasoline composition of claim 1 wherein said R and R' groups are arylalkyl groups.
18. Gasoline composition of claim 10 wherein said additive is in the amount of between about 0.02 and 2.0 theories, said additive being nickel di[bis(isodecyl) orthophosphate].
